UNITED STATES PATENT OFFICE.

HERMAN C. PRIESE, OF CHICAGO, ILLINOIS.

HOPPER-CAR.

1,077,809.

Specification of Letters Patent.

Patented Nov. 4, 1913.

Application filed June 15, 1910. Serial No. 563,837.

To all whom it may concern:

Be it known that I, HERMAN C. PRIESE, a citizen of the United States, residing in Chicago, in the county of Cook and State of Illinois, have invented a new and useful Improvement in Hopper-Cars, of which the following is a specification.

My invention has for an object the providing of a hopper car, for coal and ore, in which the doors closing the hopper bottom may be actuated by a motor such as an ordinary air-cylinder, such motor being itself controlled from air-reservoirs in each car or from the air line of the train, permitting a single car or a series or entire train of such cars to be dumped simultaneously by a single impulse from such air control; and the invention has for further objects such other improvements in structure or function as may be found to obtain in the devices hereinafter described or claimed.

In the accompanying drawings, forming a part of this specification, and in which like reference numerals indicate like parts in all figures, Figure 1 is a longitudinal view of the entire car, the air-cylinder end being shown in side elevation and the other end in longitudinal vertical section; Fig. 2 is a transverse sectional view on the line 2, 2 of Fig. 1; Fig. 3 is a detailed front elevational view of the air-cylinder control and hand-wheel operating devices of the longitudinal rock-bars that transmit movement to the hopper doors; Fig. 4 is a bottom plan view of said hopper doors and the supporting and operating devices immediately connected therewith; Fig. 5 is a detailed perspective view of one of said doors secured to the pair of swinging arms that immediately support it.

10 is the steel hopper of the car having in its bottom the dump opening 11, normally closed by the pair of laterally swinging doors 12, 12, each of said doors being mounted on and secured to the inner ends of the pair of swinging arms 13, 13. The inner end of each of said arms 13 is pivotally connected to and supported on the upper end 14 of a rock-arm 15 whose lower end 16 is pivotally mounted on the supporting bracket 17, one of said brackets 17 being secured to and depending from the bottom of the hopper at each end of the dump opening. The outer end of each swinging arm 13 is pivotally connected, at 18, to the lower end of a

swinging rock-arm 19 whose upper end 20 is rigidly secured to the rock-shaft 21, one of said rock-shafts 21 extending longitudinally along each side of the bottom of the hopper at about the level of the underframe of the car. These rock-shafts 21 are extended forward to a position opposite the air-cylinder 22 that is positioned transversely of the car and secured to the top of the car-underframe below the forward inclined end of the hopper. A pair of lever-arms 23, 24 are respectively secured to and project upward from the said forward ends of the rock-shafts 21. The upper ends of said lever-arms 23, 24 are linked by chains 25 to the drum 26 on the horizontal rotatable shaft 27 whose forward end is provided with the hand-wheel 28; so that when it is desired to open the dump doors by hand, the said hand-wheel may be rotated, winding said chains upon said drum and thereby drawing inward the upper ends of said lever-arms 23, 24, thus correspondingly rocking the rock-shafts 21 and thereby swinging outward the rock-arms 19 that resultantly swing outward the swinging arms 13 upon which the dump doors are secured, thus throwing said dump doors laterally outward until they entirely clear the dump opening of the hopper. But when it is desired to open the dump doors by means of the air-cylinder motor, the hand actuated drum and chains are idle and the lever-arms 23, 24 are drawn in toward each other by the links 29, 30 that are pivotally connected to said lever-arms respectively and respectively link said lever-arms to the respective upper ends of the downwardly inclined levers 31, 32. The lower end of the lever 31 is pivotally connected to the fixed projection 33 of the closed cylinder-end 34 of the air-cylinder; and the lower end of the lever 32 is pivotally connected to the outer end of the piston rod 35 of said air-cylinder, so that said lever 32 is thus a floating lever pivotally connected at its lower end to the piston rod and at its upper end to the link 30 that links it with the lever arm 24. And this floating lever 32 is cross-linked by the link connection 36 with the lever 31, whose upper end is, as before stated, linked by link 29 to lever-arm 23. By this arrangement of levers and links, which is clearly shown in Fig. 3 of the drawings, it is provided that the outward driving of the piston of the air-cyl-

110

inder throws outward the lower end of the lever 32, swinging said lever on its pivotal connection with the link 36 as a fulcrum and thus simultaneously drawing inward on the link that connects the upper end of lever 32 with the lever-arm 24, and drawing oppositely on the link 36 that links said lever 32 with the lever 31, so that lever 31 and with it link 29 and lever 23 are drawn inward at the same time that link 30 and lever 24 are drawn inward. This actuation of the floating lever 32 by the piston rod 35, such lever 32 drawing simultaneously and oppositely upon the link 30 and link 36, obviously 5 equalizes the pulls simultaneously transmitted to the lever-arms 23 and 24 respectively, so that said lever-arms 23 and 24 tend to be moved equally and simultaneously, in opening the doors, notwithstanding the 10 fact that a variable strain may be imposed on the opposite rock-shafts 21 by the possible differences in the load resting upon the respective dump doors that are actuated from said respectively opposite rock-shafts. 15 When the hopper has been cleared, the air pressure in the air-cylinder is released, and the dump doors swing back into their closed position, coming to a stop at such closed position by reason of the contact of their mutually meeting edges along the longitudinal median line of the dump opening and also by reason of the engagement of their upwardly extended outer flanges 37 with the fixed downwardly extended flanges 38 on either 20 side of the dump opening of the hopper. Such swinging back of the dump doors into closed position is induced by their tendency to gravitate from the upward position into which their opening movement shifts them, 25 the pivot points of their supporting members being so positioned as to facilitate this downward movement into closed position, and the said closing movement is consummated by the coiled springs 39 secured to 30 and coiled about the struts 40 that brace the depending brackets at either end of the dump opening, the free ends of said coiled springs being respectively secured at 41 to the respective rock-arms that support the 35 lower ends of the swinging arms upon which the dump doors are mounted,—these springs being tensioned as the dump doors are forcibly opened, and such tension acting to impel the doors to closed position when the power 40 holding the doors open is released.

It is obvious that the mechanism above described provides an entirely simple and positive method of motor control for the dump opening of a hopper car, and permits 45 a single car or a series or entire train of such cars to be dumped simultaneously by a single application of the power transmitted through the power or air-line of such series or train.

50 My invention is hereinabove set forth as

embodied in one particular form of construction, but I do not limit it thereto or to less than all the possible forms in which said invention as hereinafter claimed may be embodied and distinguished from prior devices. 70

I claim:—

1. In a hopper-bottom railroad-car, in combination: a hopper having a central discharge; longitudinal doors closing the discharge of said hopper and bodily movable laterally outward; upwardly extending rock arms supporting the said doors from below; operating connections for opening said doors; and a power-operated motor for 75 actuating the said operating connections to open said doors positively; substantially as specified. 80

2. In a hopper-bottom railroad-car, in combination: a hopper having a central discharge; longitudinal doors closing the discharge of said hopper and bodily movable laterally outward; upwardly extending rock arms supporting the said doors from below; operating connections for opening said doors; and a motor-cylinder for actuating the said operating connections to open said doors 85 positively; substantially as specified. 90

3. In a hopper-bottom railroad-car, in combination: a hopper having a central discharge; longitudinal doors closing the discharge of said hopper and bodily movable laterally outward; upwardly extending rock arms supporting the said doors from below; operating connections for opening said doors; and an air-cylinder for actuating the said operating connections to open said doors 95 positively; substantially as specified. 100

4. In a hopper-bottom railroad-car, in combination: a hopper having a central discharge; longitudinal doors closing the discharge of said hopper and bodily movable laterally outward, said doors being mounted on laterally swinging arms; operating connections for opening said doors; and a power-operated motor for actuating the said operating connections to open said doors 105 positively; substantially as specified. 110

5. In a hopper-bottom railroad-car, in combination: a hopper having a central discharge; longitudinal doors closing the discharge of said hopper and bodily movable laterally outward, said doors being mounted on laterally swinging arms; operating connections for opening said doors; and a 115 motor-cylinder for actuating the said operating connections to open said doors positively; substantially as specified. 120

6. In a hopper-bottom railroad-car, in combination: a hopper; doors closing the discharge of said hopper, said doors being mounted on laterally swinging arms and bodily movable outward; rock-shafts longitudinal with the car and connected with said swinging arms; and a power-operated motor 125 130

and connections for actuating said rock-shafts to open said doors positively; substantially as specified.

7. In a hopper-bottom railroad-car, in combination: a hopper; doors closing the discharge of said hopper, said doors being mounted on laterally swinging arms and bodily movable outward; rock-shafts longitudinal with the car and connected with said swinging arms; and a motor-cylinder and connections for actuating said rock-shafts to open said doors positively; substantially as specified.

8. In a hopper-bottom railroad-car, in combination: a hopper; doors closing the discharge of said hopper, said doors being mounted on laterally swinging arms and bodily movable outward; rock-shafts longitudinal with the car and connected with said swinging arms; and an air-cylinder and connections for actuating said rock-shafts to open said doors positively; substantially as specified.

9. In a hopper-bottom railroad-car, in combination: a hopper; doors closing the discharge of said hopper; operating connections for opening said doors; a power-operated motor for actuating said operating connections to open said doors positively; a spring-device tensioned by the opening of said doors and acting to press them back into closed position upon the releasing of the power-driven opening connections; substantially as specified.

10. In a hopper-bottom railroad-car, in combination: a hopper having a central discharge; longitudinal doors closing the discharge of said hopper and bodily movable laterally outward; said doors being mounted on pivotally swinging arms having their pivotal points disposed in positions adapting said doors to gravitate toward closed position; operating connections for opening said doors; and a power-operated motor for actuating said operating connections to open said doors positively; substantially as specified.

11. In a hopper-bottom railroad-car, in

combination: a hopper having a central discharge; longitudinal doors closing the discharge of said hopper and bodily movable laterally outward; said doors being mounted on pivotally swinging arms having their pivotal points disposed in positions adapting said doors to gravitate toward closed position; operating connections for opening said doors; and a manipulative device for actuating said operating connections to open said doors positively; substantially as specified.

12. In a hopper-bottom railroad-car, in combination: a hopper having a central discharge; longitudinal doors closing the discharge of said hopper and bodily movable laterally outward; said doors being mounted on pivotally swinging arms having their pivotal points disposed in positions adapting said doors to gravitate toward closed position; operating connections for opening said doors; and a spring device tensioned by the opening of said doors and acting to press them back toward closed position; substantially as specified.

13. In a hopper-bottom railroad-car, in combination: a hopper; doors closing the discharge of said hopper and bodily movable laterally outward; said doors being mounted on pivotally swinging arms having their pivotal points disposed in positions adapting said doors to gravitate toward closed position; operating connections for opening said doors; a power-operated motor for actuating said operating connections to open said doors positively; and a spring device tensioned by the opening of said doors and acting to press them back toward closed position; substantially as specified.

In testimony whereof I hereunto set my hand in the presence of two subscribing witnesses.
